[57] ABSTRACT

A mineral mining installation with a multi-section conveyor on which is guided a plough provided with a sword plate. The conveyor channel sections each have two E-shaped members attached to a barrier plate which is in turn connected to the goaf side of the conveyor. A narrow gap is produced between these two members: which members define upper and lower guide passages for a chain used to drive the plough. The sword plate extends through a gap formed between the lower ends of the conveyor and the members. The outer face of each of the members has ribs thereon for connection with shifting rams and the central limb of each member projecting towards the conveyor is of hollow reinforced construction. These webs can be detachable from the remainder of the members.

MINERAL MINING INSTALLATIONS

The present invention relates to mineral mining installations.

It is known to provide a mineral mining installation composed of a multi-section conveyor on which is guided a winning machine. The machine or plough has a sword plate extending beneath the conveyor and this sword plate is guided at the stowage or goaf side of the conveyor. The guidance arrangement usually takes the form of components connected to the goaf side of the conveyor to form guide channels or passages for receiving a chain used to drive the winning machine along the conveyor. The drive forces are transmitted from the chain to the winning machine via the sword plate. The sword plate usually has some form of guide means at its outer end which is disposed within the lower of the guide passages. Special measures may be necessary to ensure that the guide means is accurately guided in this lower passage. The guide passages may be produced by E-shaped brackets which are attached to the goaf side of the conveyor. Usually these brackets are short in relation to the length of the conveyor sections and disposed at a considerable distance apart so that additional devices are required to bridge over the gaps between these brackets. In another construction a number of spacers are attached to each of the conveyor channel sections to vertically separate the guide passages from one another and a single cover or cap is used to shield the passages from the goaf zone. The cap is especially heavy and unwieldy and the overall construction is cumbersome and generally disadvantageous. Another disadvantage of the prior art is that the known guidance systems are not wholly suitable for transmitting shifting forces to the conveyor.

A general object of this invention is to provide an improved installation of the aforementioned kind.

SUMMARY OF THE INVENTION

According to the invention there is provided a mineral mining installation comprising a scraper chain conveyor composed of a plurality of channel sections joined end-to-end and at least two guide members disposed closely adjacent one another and attached to one side of each channel section, the guide members being substantially E-shaped in cross-section with upper and lower flanges and a central web, adjoining a main wall, the guide members being disposed outwardly from the conveyor so as to form upper and lower chain guide passages. Normally barrier plates would be disposed between the guide members and the conveyor channel sections. Preferably a small gap is disposed between the guide members allocated to each channel section of the conveyor as there is between the adjacent guide members of two adjacent conveyor channel sections. These gaps enable the chain to be observed and enable the channel sections to be angularly deflected in relation to one another to a limited extent.

The guide members can be constructed to enable the shifting forces to be transmitted to the conveyor. By having two guide members for each channel section the weight of the individual members is kept within acceptable limits and these members can thus be transported and handled without undue difficulty. Moreover by making the members of identical construction and preferably completely symmetrical the members can be

interchanged and vertically re-orientated to cope with wear.

Preferably, the central web of each guide member is of hollow reinforced construction. This web may have a number of cross pieces projecting towards the conveyor and spaced apart longitudinally of the conveyor to form a series of U-shaped compartments open towards the conveyor. The upper surfaces of the cross pieces form a running surface for the sections of a chain disposed in the upper guide passage. Each of the apertures preferably has an aperture therethrough for receiving a bolt used to secure the associated guide member to the conveyor. These apertures can be in the form of vertical slots enabling the guide member to be readily adjusted in relation to the conveyor.

In accordance with a further feature of the invention the outer face of the main wall of each guide member is formed with two longitudinal ribs having upwardly and downwardly directed flanges. At least one of the flanges of the longitudinal ribs has a series of apertures therein to enable shifting rams to be connected to the guide members. The shifting forces can thus be distributed and transmitted through the reinforced central web of the guide members to the conveyor. The guide members may be an integral casting although a multi-part welded construction is also possible. In another embodiment the central web is detachable from the remainder of each guide member. This web may be constructed from two plates interconnected at their ends and crosspieces arranged between said plates and spaced apart longitudinally of the conveyor. In a specific construction four such cross-pieces are provided for each central web, the inner faces of the plates and the crosspieces defining reception zones for fixing bolts which are used to secure the web and the remainder of the associated guide members to the conveyor.

Further according to the invention there may be provided fixing devices for clamping the guide members to the conveyor, each of said devices being engageable with a shaped aperture provided in the transition zone between the main wall and the upper flange of the associated guide member. Each fixing device may have a hook-like projecting arm which engages with the guide member in the region of the shaped aperture.

The invention may be understood more readily and various other features of the invention may become more apparent from consideration of the following description.

BRIEF DESCRIPTION OF DRAWINGS

Embodiments of the invention will now be described, by way of examples only, with reference to the accompanying drawings, wherein:

FIG. 1 is a diagrammatic side view of a mineral mining installation made in accordance with the invention;

FIG. 2 shows at the left-hand side a sectional plan view of one part of the installation taken along the line II-II of FIG. 1, and at the right-hand side a plan view of the other part of the installation taken along the line II'-II' of FIG. 1;

FIG. 3 is an end view of the installation taken in the direction of the arrow III of FIG. 1;

FIG. 4 is a diagrammatic side view of a further mineral mining installation made in accordance with the invention with the conveyor omitted for the sake of clarity;

FIG. 5 shows at the left-hand side a sectional plan view of one part of the further installation taken along the line V—V of FIG. 4 and at the right-hand side a plan view of the other part of the installation taken along the line V'—V' of FIG. 4;

FIG. 6 is an end view of the further installation taken in the direction of the arrow VI of FIG. 4;

FIG. 7 is a side view of a detachable central web for use with the installations shown in FIGS. 1 to 6.

DESCRIPTION OF PREFERRED EMBODIMENTS

Referring initially to FIGS. 1 to 3, there is shown a mineral mining installation with a scraper chain conveyor generally denoted 1. The conveyor 1 is, in the known manner, composed of individual channel sections joined end-to-end and movable to a limited extent in respect of one another. Each of these channel sections is constructed from profiled side walls 1' of generally sigma-shaped cross-section connected to a floor 1''. A scraper chain assembly, which is omitted from the drawings for the sake of clarity, is circulated along the floors 1'' of the channel sections and guided by the side walls 1'. A winning machine such as a plough would be guided for movement along the mineral face side of the conveyor 1, i.e. along the walls 1' adjacent the face. On the stowage or goaf side of the conveyor there is provided barrier plates 18 of L-shaped cross-section. These plates 18 each have an upper flange extending outwardly from the conveyor 1 and the plates 18 are arranged end-to-end along the conveyor 1 to form a continuous wall. Usually a single barrier plate 18 extends along each of the channel sections of the conveyor 1. A series of guide members 2,2' are attached to the barrier plates 18 and more particularly two such members 2,2' are allocated to each channel section of the conveyor. The length of these two members 2,2' is such that a narrow gap 22 is produced at the centre of each channel section.

As shown in FIG. 3, each guide member 2,2' is basically of E-shaped cross-section with a main outer wall 14, an upper flange 14' a lower flange 14'' and a central web 9. The guide member 2,2' may be formed as a casting. The upper flange 14' and the central web 9 of each guide member 2,2' is affixed to the associated barrier plate 18 so as to form two guide passages, namely an upper guide passage 19 and a lower guide passage 24. The substantially continuous passages 19, 24 thus formed by the collective guide members 2,2' are separated from one another by the webs 9 and serve to receive an endless chain (not shown) used for driving the winning machine or plough along the conveyor. The return run of the chain is disposed in the passages 19 whilst the haulage run of the chain is disposed in the passages 24.

A gap 25 is formed between the lower part of the barrier plates 18 and the side walls 1' of the conveyor channel sections on the one hand and the lower flanges 14'' of the guide members on the other hand. This gap 25 receives a terminal portion of a sword plate (not shown) attached to the winning machine and extending beneath the conveyor in known manner. The sword plate serves to guide the machine and transmits the driving force of the chain thereto. The end of the sword plate is disposed within the guide passage 24 and one or more guide bodies (not shown) would connect the sword plate to the haulage run of the chain in the pas-

sage 24 and these guide bodies would be guided for movement within the passage 24.

As shown in FIG. 2, the central web 9 of each guide member 2,2' is basically a hollow reinforced structure 5 provided with spaced-apart crosspieces 90 to form U-shaped compartments 10,11,12,13 open towards the associated barrier plate 18. Each of these crosspieces 90 is itself provided with an aperture 15 extending through the main wall 14 of the guide member 2,2'. 10 Fixing bolts 16 are inserted through these apertures 15 to pass through bores in the associated barrier plate 18 and thereby serve to attach the guide members 2,2' to the plate 18. Additional fixing means generally denoted 91 are provided at the region of the upper flanges 14' 15 of the members 2,2'. The apertures 15 are preferably in the form of vertically-orientated slots to permit the guide members 2,2' to be positioned vertically prior to tightening of the bolts 16. Shaped washers 23 are provided under the head of each of the bolts 16 at the outside of the wall 14. The upper faces of the crosspieces 90 form a running surface 20 for the return run of the drive chain.

The outer face of the wall 14 of each guide member 2,2' is provided with two longitudinal ribs 3,4 disposed 25 centrally of the member 2,2' and generally aligned with the web 9. Vertical ribs 5 are connected between the ribs 3,4 and spaced apart longitudinally of the members 2,2'. The main ribs 3,4 are curved over portions of their length in the region of the apertures 15 and the ribs 3,4 30 are provided with small flanges 6,7 extending generally parallel to the main wall 14. The upper flange 6 is provided with recesses 8 spaced apart longitudinally of the member 2,2' and serve to locate shifting rams (not shown). The forces produced by these rams which act 35 to bodily move the conveyor and associated parts towards the mineral face are in the main directed through the reinforced central part of the members 2,2'.

FIGS. 4 to 6 depict a further embodiment of the invention where the conveyor is omitted except for the ghost outline of the goaf side wall 1' of one of the channel sections shown in FIG. 6, so that only the barrier plates 18 and the guide members 2,2' are shown in detail. For convenience like reference numerals throughout FIGS. 4 to 6 denote the same features described above and illustrated in FIGS. 1 to 3. As shown in FIGS. 4 to 6 two guide members 2,2' are attached to the barrier plate 18 provided at the goaf side of the conveyor. Each guide member 2,2' is again of E-shaped cross-section with an upper flange 14', a central web 9 45 and a lower flange 14'' and a main wall 14.

Each member 2,2' is symmetrical about the horizontal plane m so that they can be inverted with either the flange 14 or the flange 14'' at the top. The members 2,2' are fabricated by casting and/or welding. As shown in FIG. 5 the central web 9 is a body 17 provided with apertures 15 receiving bolts 16, located in bores in the barrier plate 18. The heads of the bolts 16 are disposed 50 at the outside of the apertures in the main wall 14 and shaped washers preferably underlie these heads. Ribs 3, 4 are welded onto or otherwise produced at the outside of the main wall 14 and these ribs 3,4 extend over the entire length of the member 2,2'. A plate 21 is connected across the edges of the ribs 3,4 to lie parallel to the wall 14. Apertures 21' are provided in the plate 21 to permit access to the bolts 16. The edges of the plate 21 are also provided with recesses 21'' spaced apart 55 60 65

longitudinally of the plate 21. The recesses 21" permit connection with shifting rams (not shown) and the shifting forces produced by these rams are in the main transmitted to the conveyor via the reinforced web 9.

Additional fixing devices 26 for fixing the members 2,2' to the barrier plate 18 are disposed at the region of the upper flanges 14'. Each device 26 has a hook-like projecting arm 27 which is received by a shaped aperture 18 provided in the transition region between the main wall 14 and the upper flange 14' of the associated member 2,2' to lock the member 2,2' to the device 26. A similarly shaped aperture 28 is provided in the transition region of the flange 14" and the wall 14 of each member to permit the members 2,2' to be inverted. Where the members 2,2' are formed by bending and welding before the flanges 14', 14" are produced by bending an H-shaped cut away portion (FIG. 4) produced in the position where it is desired to form the apertures 28 will result in the automatic formation of the aperture when the flanges 14', 14" are bent over.

Each device 26 has a certain amount of clearance in respect of the upper flange 14' of the associated member 2,2' and this enables the member 2,2' to be released and re-connected in an inverted position with the flange 14" now at the top. Such re-connection may be desirable when a certain amount of wear has occurred.

Each device 26 is attached to the barrier plate 18 with the aid of a bolt 32 which extends through a web 33 of the device 26. Each device has extensions 31 which abut the barrier plate 18 to provide leverage between the point of application of the bolt 32 and the barrier plate 18, so that the device 26 can clamp the member 2,2' to the barrier plate 18 with considerable force.

The devices 26 each have an upright plate 34 at the outerside of the construction and this plate 34 has bores therein the enable accessories such as cable clamps or the like to be attached to the device 26.

In the above-described constructions the central web 9 of each member 2,2' is either formed integrally with, or else rigidly attached to, the remainder of the member 2,2'. It is however feasible to use detachable webs connected to the member 2,2' with the aid of the fixing bolts 16 for example. An example of a detachable web 9 is shown in FIG. 7.

As shown in FIG. 7 the web 9 is formed from two parallel plates 40,41 which have converging ends 42 that are welded together. The width of the plates 40, 41 in a plane perpendicular to the drawing is equal to the width of the passages 19, 24 and to the distance between the inner face of the main wall 14 of the associated member 2,2' and the outer face of the barrier plate 18. A number, in this case four, of cross-pieces 43-46 are welded between the plates 40,41 with the crosspieces 43, 46 near the ends of the webs 9 and the crosspieces 44,45 near the centre. The distance between the crosspieces 44,45 and the distance between the plates 40, 41 is somewhat greater than the diameter of the fixing bolts 16. Three bolts can be used in the position shown to affix the web 9 to the remainder of the structure and clamp the member 2,2' to the barrier plate.

The web 9 thus constructed is symmetrical about the plane m and hence can be used with the plate 40 or 41 uppermost. In the case of wear the web 9 can thus be inverted and in due course replaced.

We claim:

1. A mineral mining installation comprising: a scraper chain conveyor having a plurality of channel sections joined end-to-end, a mineral winning machine mounted for movement along one side of the conveyor, two guide members attached to the other side of each channel section, each of the guide members being generally E-shaped in cross section with upper and lower flanges and a central web adjoining a main wall, the central web having a number of crosspieces projecting towards the conveyor and spaced apart longitudinally of the conveyor to form compartments open towards the conveyor, the flanges and the central web of the guide members being directed towards the conveyor to form upper and lower guide passages defined between the central web and the upper and lower flanges, respectively, a drive chain disposed between the lower extremity of the other side of each channel section and the lower flanges of the associated guide members, and a sword plate connected to the machine and extending through at least one of said gaps to connect with the chain disposed in the lower guide passage.

2. An installation according to claim 1, wherein each of said crosspieces has an aperture therethrough for receiving a bolt used to secure the associated guide member to the conveyor.

3. An installation according to claim 1, wherein upper surfaces of the crosspieces form a running surface for the sections of a chain disposed in the upper guide passage.

4. An installation according to claim 1, wherein the guide members are of identical construction.

5. An installation according to claim 1, wherein a gap is formed between the guide members connected to each channel section.

6. An installation according to claim 1, wherein each guide member is constructed in a symmetrical manner so that it can be inverted vertically and re-connected to the conveyor.

7. An installation according to claim 1, wherein barrier plates are connected to said one side of the conveyor and the guide members allocated to each channel section are secured to one of said barrier plates.

8. A mineral mining installation comprising: a scraper chain conveyor having a plurality of channel sections joined end-to-end, a mineral winning machine mounted for movement along one side of the conveyor, guide members attached to the other side of each channel section, each of the guide members being generally E-shaped in cross section with upper and lower flanges and a central web adjoining a main wall, the central web being detachably mounted on said main wall and formed from two plates interconnected at their ends with crosspieces arranged between said plates and spaced apart longitudinally of the conveyor, the flanges and the central web of the guide members being directed towards the conveyor to form upper and lower guide passages defined between the central web and the upper and lower flanges, respectively, a drive chain disposed within the upper and lower passages, a gap disposed between the lower extremity of the other side of each channel section and the lower flanges of the associated guide members, and a sword plate connected to the machine and extending through at least one of said gaps to connect with the chain disposed in the lower guide passage.

9. An installation according to claim 8, wherein the guide members are of identical construction and a gap is formed between the guide members connected to each channel section.

10. An installation according to claim 8, wherein each guide member is constructed in a symmetrical manner so that it can be inverted vertically and re-connected to the conveyor.

11. An installation according to claim 8, wherein barrier plates are connected to said one side of the conveyor and the guide members allocated to each channel section are secured to one of said barrier plates.

12. An installation according to claim 8, wherein four crosspieces are provided for each central web, the inner faces of the plates and the crosspieces defining reception zones for fixing bolts which are used to secure the web and the remainder of the associated guide members to the conveyor.

13. A mineral mining installation comprising: a scraper chain conveyor having a plurality of channel sections joined end-to-end, a mineral winning machine mounted for movement along one side of the conveyor, two guide members attached to the other side of each channel section, each of the guide members being generally E-shaped in cross section with upper and lower main flanges and a central web adjoining a main wall, the outer face of the main wall of each guide member being formed with two longitudinal ribs having upwardly and downwardly directed flanges, the main flanges and the central web of the guide members being directed towards the conveyor to form upper and lower guide passages defined between the central web and the upper and lower main flanges, respectively, a drive chain disposed within the upper and lower passages, a gap disposed between the lower extremity of the other side of each channel section and the lower main flanges of the associated guide members, and a sword plate connected to the machine and extending through at least one of said gaps to connect with the chain disposed in the lower guide passage.

14. An installation according to claim 13, wherein the guide members are of identical construction and a gap is formed between the guide members connected to each channel section.

15. An installation according to claim 13, wherein each guide member is constructed in a symmetrical manner so that it can be inverted vertically and re-connected to the conveyor.

16. An installation according to claim 13, wherein barrier plates are connected to said one side of the conveyor and the guide members allocated to each channel section are secured to one of said barrier plates.

17. An installation according to claim 13, wherein

the longitudinal ribs are interconnected by upright ribs spaced apart longitudinally of the guide member.

18. An installation according to claim 13, wherein at least one of the flanges of the longitudinal ribs has a series of apertures therein to enable shifting rams to be connected to the guide members.

19. A mineral mining installation comprising: a scraper chain conveyor having a plurality of channel sections joined end-to-end, a mineral winning machine mounted for movement along one side of the conveyor, two guide members attached to the other side of each channel section, each of the guide members being generally E-shaped in cross section with upper and lower flanges and a central web adjoining a main wall, the central web of each guide member having apertures therein receiving bolts serving to fix the guide member to the conveyor, each guide member being of symmetrical construction permitting the member to be inverted vertically and re-connected to the conveyor, the outer face of the main wall of each guide member being formed with two longitudinal ribs with a plate being connected between said ribs to lie parallel to said main wall, said plate having apertures therein permitting access to said bolts and recesses at its edges for connection to shifting rams, the flanges and the central web of the guide members being directed towards the conveyor to form upper and lower guide passages defined between the central web and the upper and lower flanges, respectively, a drive chain disposed within the upper and lower passages, a gap disposed between the lower extremity of the other side of each channel section and the lower flanges of the associated guide members, and a sword plate connected to the machine and extending through at least one of said gaps to connect with the chain disposed in the lower guide passage.

20. An installation according to claim 19, wherein a gap is formed between the guide members connected to each channel section.

21. An installation according to claim 19, wherein barrier plates are connected to said one side of the conveyor and the guide members allocated to each channel section are secured to one of said barrier plates.

22. An installation according to claim 19, wherein there is provided fixing devices for clamping the guide members to the conveyor, each of said devices being engageable with a shaped aperture provided in the transition zone between the main wall and the upper flange of the associated guide member.

23. An installation according to claim 22, wherein each fixing device has a hook-like projecting arm which engages with the guide member in the region of the shaped aperture.
